[57] CLAIM

The ornamental design for a digitizer for a graphic tablet, as shown and described.

DESCRIPTION

FIG. 1 is a top, front, left side perspective view of a digitizer for a graphic tablet showing our new design; FIG. 2 is a right side elevational view thereof on an enlarged scale;

FIG. 3 is a rear elevational view thereof on an enlarged scale;

FIG. 4 is a bottom plan view thereof on enlarged scale;

FIG. 5 is a top, front, left side perspective view thereof with the document overlay partially raised.
